UNITED STATES PATENT OFFICE

172,006

SPOON OR OTHER ARTICLE OF FLATWARE

Edward J. Conroy, Meriden, Conn., and Samuel Ayres, Jr., Boston, Mass.

Application June 15, 1953, Serial No. 25,503

Term of patent 14 years

(Cl. D54—12)

To all whom it may concern:

Be it known that we, Edward J. Conroy and Samuel Ayres, Jr., citizens of the United States, residing respectively at Meriden, county of New Haven, State of Connecticut, and Boston, county of Suffolk, Commonwealth of Massachusetts, have invented a new, original, and ornamental Design for a Spoon or Other Article of Flatware, of which the following is a specification, reference being had to the accompanying drawing forming a part thereof.

Fig. 1 is a front elevational view of a spoon showing the essential features of our new design in full lines;

Fig. 2 is an enlarged cross section taken on the line 2—2 of Fig. 1;

Fig. 3 is an enlarged cross section taken on the line 3—3 of Fig. 1; and

Fig. 4 is a perspective view of the spoon illustrated in Fig. 1.

The back of the spoon handle is substantially plain and follows the contours of the front as shown in Figs. 2 and 3.

The design is intended for use on sets comprising spoons, forks, knives and similar articles of flatware.

We claim:

The ornamental design for a spoon or other article of flatware, substantially as shown and described.
